SAFETY-PILOT GAS VALVE

Henry Dreyfuss, South Pasadena, Calif., assignor to
Minneapolis-Honeywell Regulator Company, Minne-
apolis, Minn., a corporation of Delaware

Application November 8, 1955, Serial No. 38,800

Term of patent 14 years

(Cl. D78—1)

FIG. 1

FIG. 2

Figure 1 is a perspective view from one side and one end of the safety-pilot gas valve embodying my design; and

Figure 2 is a perspective view, to a reduced scale, of the structure of Figure 1 but from the other side and end thereof.

I claim:

The ornamental design for a safety-pilot gas valve, substantially as shown.
